UNITED STATES PATENT OFFICE.

WEBB JAY, OF CHICAGO, ILLINOIS.

SUCTION-ACTUATED PUMPING DEVICE.

1,390,617.

Specification of Letters Patent. Patented Sept. 13, 1921.

Continuation in part of application Serial No. 89,524, filed April 7, 1916. This application filed May 10, 1917. Serial No. 167,638.

To all whom it may concern:

Be known that I, WEBB JAY, a citizen of the United States, residing at Chicago, in the county of Cook and State of Illinois, 5 have invented new and useful Improvements in Suction-Actuated Pumping Devices, of which the following is a specification, reference being had to the accompanying drawings, forming a part thereof.

10 The application is a continuation of my previous application, Serial No. 89,524, filed April 7th, 1916, and allowed October 5th, 1916. The purpose of the invention herein shown is similar to that of my pending application, Serial No. 868,580, filed October 26th, 1914, namely, in general, to provide means for transferring liquid (such as liquid fuel for use in an internal combustion engine) from a low level supply tank to an 15 elevated receptacle or reservoir from which it may flow by gravity to the point of use, as the carburetor of the engine. The invention consists in the features and elements 20 of construction described and shown in the drawings as indicated in the claims.

In the drawings:

Figure 1 is a diagrammatic view of the nature of a side elevation, showing in dotted outline a portion of an internal combustion 30 engine of an automobile, and associated therewith the various parts and elements of the present invention.

Fig. 2 is an axial section of the pumping device which embodies this invention in one 35 of its forms.

Fig. 3 is a similar view of a modified form of the pumping device.

Fig. 4 is a vertical axial section broken away to condense the view of the auxiliary 40 reservoir which may be supplied by this pumping device in one of its forms.

Fig. 5 is a view similar to Fig. 2, showing a further modification.

Fig. 6 is an axial section of the auxiliary 45 reservoir in a different form from that shown in Fig. 4.

Fig. 7 is a section at the line 7-7, on Fig. 2.

Briefly, the pumping device in the form 50 in which it is shown comprises a suction-operated piston and a liquid-pumping piston, mechanically connected together for actuation of the latter by the former. It may be understood that when the device is used in connection with an internal combustion en-

gine, the source of suction may be the intake manifold of the engine from which any suitable pipe or conduit may connect with a suction port, A¹, in the suction chamber, A, in which the suction-operated piston, B, is 60 disposed. In addition to the suction port, A¹, the chamber, A, has an air inlet port, A³. In all the forms illustrated, means is provided for alternating the dominance of the suction and the atmospheric pressure operating through the ports, A¹ and A³, respectively. In the form shown in Fig. 2, this means consists in making the air inlet port quite large relatively to the suction port and providing a valve to control said air inlet 65 port operated by the movement of the piston. In the form shown in Fig. 3 the means for this purpose consists in providing separate valves for controlling these two ports, and connections by which both of the valves 70 are operated by the movement of the piston for opening one valve when the other is closed, and vice versa. In the form shown in Fig. 5, the means for accomplishing the same result consists in making the suction 75 port relatively quite large with comparison to the air inlet port and providing a valve for controlling the suction port operated by the movement of the piston. In the form shown in Fig. 2 the atmosphere-port-control- 80 valve, D, is carried by a stem, D¹, which plays in an axial cavity or pocket in the piston, B, being guided somewhat loosely in the collar or bushing, b¹, at the entrance of said pocket; and the upper end of said stem, 85 D¹, is pivotally connected to the end of the approximately horizontal arm, E¹, of a bell crank lever, E E¹, which is fulcrumed at its angle on a bracket, F, mounted in fixed position on the cylinder; a spring, G, being 90 provided connected to the end of the arm, E, of the bell crank lever, and stressed back past the fulcrum of the lever to a fastening point at f on the bracket, F. The position of the valve, D, when the bell crank lever 95 is in such position that the stress of the spring is a line through the fulcrum of the lever, is intermediate between its wide open and its fully closed position. The connection of the valve stem, D¹, with the lever 100 arm, E¹, is slotted as shown, at d¹, to permit the valve a certain range of movement without moving the lever, and the lever a certain range of movement without moving the valve; and the stem, D¹, of the valve is 110

threaded below the port, A³, and carries on its threaded portion two nuts, d² and d³, respectively above and below the guide collar, b¹, which nuts may be adjusted to engage the guide collar at predetermined limits of the movement of the piston in the cylinder, for causing the piston in said movements to start the movement of the valve either toward or away from the seat as the case may be, the movement being finished in either direction by the reaction of the spring, G, after the bell crank lever, E E¹, has been rocked by the positive actuation of the piston to carry the line of stress of the spring past the fulcrum of the lever; thus giving what is commonly known as a snap action to the valve both in seating and unseating. The slotted connection of the lever to the valve stem at d¹ permits the lever to complete its movement in either direction after giving the valve by the reaction of the spring, G, its proper movement in either direction.

It will be observed that the piston, B, is actuated in opposition to the suction by a spring, H. For compactness in the structure the piston is provided with an annular pocket, B², which receives one end of the spring, H, and the head of the cylinder is provided with a corresponding annular pocket, A⁴, which receives the remainder of the spring H. The central portion of the head encompassed by the annular pocket, A⁴, is chambered out to accommodate the valve, D, and its operating and guiding connections comprising the bell crank lever, spring, etc. It is desirable to protect this central pocket from the accumulation of extraneous matter which might impede the action, and for that purpose there is provided a cap or plug, A⁵, which is marginally apertured at a⁵ to afford free atmospheric communication into the pocket and—when the valve, D, is open—through the port, A³, into the cylinder chamber, A. It will be noticed that the under side of the piston, B, is at all times exposed to atmospheric pressure, which has access through a port, f¹, between said piston, B, and the smaller piston, K. Said piston, K, is carried on the end of the stem, K¹, which connects the two pistons rigidly, and it plays in the smaller cylinder, L, which communicates,—or but for the piston, K, would communicate,—with the lower end of the cylinder chamber, A, in which the piston, B, reciprocates. The lower end of said cylinder, L, is shown connected with the stem of a T-fitting, M, which is an element in a pipe line, O, leading from the low tank, P, to the carbureter, Q, and intermediately to the auxiliary reservoir, R. Check valves, M¹ and M², in this T-fitting at opposite sides of the stem open for flow of liquid from the low level tank, P, toward the carbureter and auxiliary reservoir, R, and seat in the oppo-

site direction. Any form of check valve may be employed. In Fig. 2 the check valves are shown as very light metal disks lying loosely in restricted chambers, at one side of which they seat, while at the other side they are off their seats permitting the free flow of liquid past them.

In the form shown in Fig. 3 the suction port and the air inlet port are not materially different in size or capacity; and the alternating dominance of the suction and the atmospheric pressure is attained by providing each of these ports with a valve, the valve, T, controlling the atmosphere inlet port, and the valve, U, controlling the suction port, each being positioned at the proper side of its seat to be held onto the seat more or less by the suction or partial vacuum operating above the piston in the larger of the two piston chambers. Both valves are operatively connected with the same arm of a lever, E², fulcrumed at e on a bracket depending from the top of the chamber, the spring G, being stressed from the remote end of the lever arm which engages the valve past the fulcrum of the lever to a fixed engaging point, e¹, on the bracket, F¹, and operating, as in the previously described form, for giving snap action to the valve, that is, completing its movement in either direction after the movement has been initiated by the piston approaching the limit of its stroke in one direction or the other. In this form the spring, H, is partly accommodated in the annular pocket, B², of the piston.

In the form shown in Fig. 5 to minimize friction the piston, B, is loosely fitted to the chamber, A, and the lower end of its flange or skirt, B¹, is kept constantly submerged in liquid, such as a thick lubricating oil indicated at X, and carried in an annular trough, A², formed at the lower end of the chamber, A. In this form the springs which resist the suction-caused movement of the piston are disposed for being stretched by that movement instead of being compressed as in the other form; and for compactness of structure in view of this modification, the piston is chambered on its under side and the cylinder is provided with an annular partition, L¹, extending up into the cylinder and into the cavity of the piston, forming, in fact, the inner wall of the annular trough, A², above mentioned; and the springs, H^a, attached at their upper ends to the piston, extend down within this annular partition, being attached at their lower ends thereto at hooks, L¹⁰. As a matter of practical convenience, this partition, L¹, is formed as a continuation of the smaller cylinder, L. In this form the free admission of atmosphere behind the piston,—that is, on the opposite side from that at which it is exposed to the suction,—is obtained

through this annular member, L^1 , which is apertured at L^{11} , which constitutes the air inlet between the two pistons which in the previously described forms is afforded by 5 the port, f^1 . In this form shown in Fig. 5, the valve-controlled inlet and discharge passages for the cylinder case are seen at K^3 and K^4 , respectively, the check valves in this form being illustrated as balls, k^5 10 and k^6 .

In conjunction with any one of the three forms of pumping devices shown, the auxiliary chamber to be supplied thereby may be of either of the forms shown in Fig. 4 15 and Fig. 6 respectively. In Fig. 4 the reservoir, R , having its inlet for the liquid through the pipe, O^1 , at the bottom has the air inlet at R^1 at the top where there is desirably connected a return bend, R^2 , which 20 tends to prevent the entrance of dust and dirt which might choke the vent and gives a preferably downward discharge for any vapor or oil that may under certain possible circumstances be discharged in case of leakage 25 of the air valve upon flooding of the chamber. In this form the valve, W , for controlling the air inlet is connected by its stem, W^1 , to the float, Z , the connection being effected by an eye, Z^1 , on the float 30 engaging the stem of the valve between two stops, w^1 and w^2 , thereon, the distance between the stops providing for a certain definite range of movement of the float without actuation of the valve. The valve stem has 35 a guide, W^4 , which also furnishes a stop at W^5 , to limit the opening movement of the valve within convenient range. It will be seen that in this form the reservoir will be filled by any excess of liquid pumped beyond 40 what is necessary to supply the carbureter, and that the valve, W , will be closed by the operation of the float before the reservoir is filled, and will be opened as soon as there is any discharge of the liquid from the reservoir, such opening admitting atmospheric 45 pressure to permit the discharge freely by gravity.

In the form shown in Fig. 6 the reservoir has an air vent, r , at the top. The liquid is 50 supplied to the reservoir through an inlet tube, O^4 , extending up from the bottom where the connection is made with the pipe, O^1 , the liquid flowing over from the top of this tube, O^4 , to fill the reservoir. A valve, 55 Z^2 , is provided for closing the upper end of this tube. The valve would obviously be opened by the rise of the liquid in the tube to the point of overflow unless it is held positively seated; and for so seating it positively 60 after the reservoir is filled to a pre-determined limit, the valve is carried by a jointed link, comprising the member, Z^3 , and a bell crank member, Z^4 , the up-standing arm, Z^{40} , of said bell crank lever being 65 the element of the jointed link, and the other

arm being extended off horizontally and connected to the stem, Z^5 , of the float, Z^6 . The weight of the float, when not buoyed by the liquid in the reservoir, holds the bell crank lever and the link element, Z^3 , at the 70 position shown in dotted line, keeping the valve unseated and permitting free inflow of the liquid. As the liquid rises, eventually the float is buoyed up and lifts the lever to the position shown in full line at which the 75 two link elements are alined and the valve is positively seated. In order to cause this action for seating and the action for unseating to be instantaneous, there is provided a spring stop, z , having an angle-shaped abutment at z^1 , whose two slopes are encountered by the end of the lever arm in the upward and downward movements respectively, the apex of the angle being positioned with respect to the end of the lever so that the latter passes said apex when the valve is at an intermediate position between its wide open and fully closed position, and upon passing the apex the reaction of the spring forces the lever to the limit of its movement in one 80 direction or the other,—that is, for closing the valve when the float is rising and lifting the lever, and for opening it widely when the float is falling. A stop screw, z^4 , set into a boss at the top of the reservoir projecting down over the end of the lever may be adjusted to cause the lever to come to the proper position for seating the valve and not be thrown beyond that position when it passes the apex of the spring in the rising 85 movement of the float. In this form it will be seen that the inflow of the liquid is positively arrested when the valve is seated by the rising of the float, whereas, in the form shown in Fig. 4, the inflow may continue as long as the force of the pump is sufficient to force the liquid in against the resistance of the imprisoned and resultantly compressed air above the liquid in the reservoir. But in either form the possibility of overflow is defeated by the action of the float controlling the atmosphere inlet valve or the liquid inlet valve.

I claim:—

1. In combination, a large cylinder and a small cylinder; a large piston and a small piston rigidly connected together and operating in said cylinders respectively, the large cylinder having at the same side of the piston therein, two independent ports, one for atmosphere inlet and the other for suction connection; valve means operated by the piston movement for alternating the dominance of the suction and atmospheric pressure through said ports respectively, and valve-controlled inlet and discharge passages for the small cylinder.

2. In combination, a large cylinder and a small cylinder; a large piston and a small piston rigidly connected together and oper-

ating in said cylinders respectively, the large cylinder having at the same side of the piston therein, two independent ports, one for atmosphere inlet and the other for suction connection, one of said ports being relatively small and the other relatively large; a valve operated by the piston controlling the larger of said ports for alternating the dominance of the suction and atmospheric pressure operating through said ports respectively by the back-and forth movement of the piston; and valve-controlled inlet and discharge passages for the small cylinder.

3. In combination, a large cylinder and a small cylinder; a large piston and a small piston rigidly connected together and operating in said cylinders respectively; yielding means operating on said rigidly-connected pistons for moving them in one direction and resisting their movement in the opposite direction, the large cylinder having at the same side of the piston therein, two independent ports, one for atmosphere inlet and the other for suction connection; means operated by the movement of the pistons for alternating the dominance of the suction and atmospheric pressure operating through said ports respectively, and valve-controlled inlet and discharge passages for the small cylinder.

4. In combination, a large cylinder and a small cylinder; a large piston and a small piston rigidly connected together and operating in said cylinders respectively; a spring which resists the movement of said rigidly-connected pistons in one direction and reacts for their movement in the opposite direction, the large cylinder having at the same side of the piston therein, two independent ports, one for atmosphere inlet and the other for suction connection, and means operated by the back-and-forth movement of the pistons for alternating the dominance of the suction and atmospheric pressure operating through said ports respectively, and valve-controlled inlet and discharge passages for the small cylinder.

5. In combination, a large cylinder and a small cylinder; a large piston and a small piston rigidly connected together and operating in said cylinders respectively; a spring which yieldingly resists the movement of said pistons in one direction and reacts for moving them in the opposite direction, the large cylinder having a suction port and an atmosphere inlet port at the same side of the piston therein, one of said ports being large relatively to the other, a valve controlling said larger port, means by which the movement of the piston in opposite directions operates said valve for opening and closing to alternate the dominance of the suction and atmospheric pressure through said ports respectively, and valve-controlled

inlet and discharge passages for the small cylinder.

6. In combination, a large cylinder and a small cylinder; a large piston and a small piston rigidly connected together and operating in said cylinders respectively; the large cylinder having at the same side of the piston therein, two independent ports, one for atmosphere inlet and the other for suction connection, means for alternating the dominance of the suction and the atmospheric pressure respectively operating through said ports, for reciprocating the pistons; a spring operating on the piston to resist the suction-caused movement and retracting it in the opposite direction; and valve-controlled inlet and discharge passages for the small cylinder.

7. In combination, a large cylinder and a small cylinder; a large piston and a small piston rigidly connected together and operating in said cylinders respectively, the large cylinder having at the same side of the piston therein, two independent ports, one for atmosphere inlet and the other for suction connection, means operated by the movement of the piston for alternating the dominance of the suction and the atmospheric pressure through said ports respectively, and a spring operating on the piston in opposition to the suction-caused movement of the piston, the piston being chambered to accommodate a portion of the length of the spring.

8. In a liquid-feeding apparatus in combination with a low level supply tank and pumping means connected therewith, an elevated auxiliary tank into which said pumping means discharges, an inlet opening in said tank, a valve controlling the same, a fulcrum positioned opposite said inlet opening, a jointed link connecting the valve with said fulcrum and dimensioned to hold said valve in closed position when the pivot at the joint of said link is alined with the fulcrum pivot and said valve, and a float in said auxiliary tank connected to said jointed link and adapted to straighten it for closing the valve when the liquid reaches a predetermined level in the tank.

9. In combination a large and a small cylinder; a large piston and a small piston rigidly connected together and operating in said cylinders respectively; valve-controlled inlet and discharge passages for the small cylinder, the large cylinder having a suction port and an air inlet port which is large relatively to the suction port, said two ports being at the same side of the piston in said cylinder; a valve controlling the air inlet port and connections by which the piston operates said valve for opening it at the limit of the suction caused by the stroke of the piston.

10. In combination, a large cylinder and a small cylinder; a large piston and a small piston rigidly connected together and operating in said cylinders respectively; valve-controlled inlet and discharge passages for the small cylinder, the large cylinder having at the same side of the piston therein a suction port and an air inlet port which is larger than the suction port; a valve controlling said larger port; a lever operatively connected with the valve; a spring connected to one end of the lever and stressed past the lever fulcrum, whereby it tends to throw the valve to either limit upon being moved away from the opposite limit a certain distance, the piston being connected with the valve for initiating its movement with play at the connection for permitting the completion of the movement by the action of the spring.
- 15 11. In combination, a large cylinder, and a small cylinder, a large piston and a small piston rigidly connected together and operating in said cylinders respectively; valve-controlled inlet and discharge passages for the small cylinder, the large cylinder having at the same side of the piston therein a suction port and an air inlet port which is larger than the suction port; a valve controlling said larger port; a lever operatively connected with the valve; a spring connected to one end of the lever and stressed past the lever fulcrum, whereby it tends to throw the valve to either limit upon being moved away from the opposite limit a certain distance, the piston being connected with the valve for initiating its movement with play at the connection for permitting the completion of the movement by the action of the spring.
- 20 12. In combination, a large cylinder, and a small cylinder, a large piston and a small piston rigidly connected together and operating in said cylinders respectively; valve-controlled inlet and discharge passages for the small cylinder, the large cylinder having at the same side of the piston therein a suction port and an air inlet port which is larger than the suction port; a valve controlling said larger port; a lever operatively connected with the valve; a spring connected to one end of the lever and stressed past the lever fulcrum, whereby it tends to throw the valve to either limit upon being moved away from the opposite limit a certain distance, the piston being connected with the valve for initiating its movement with play at the connection for permitting the completion of the movement by the action of the spring.
- 25 13. In combination, a large cylinder, and a small cylinder, a large piston and a small piston rigidly connected together and operating in said cylinders respectively; valve-controlled inlet and discharge passages for the small cylinder, the large cylinder having at the same side of the piston therein a suction port and an air inlet port which is larger than the suction port; a valve controlling said larger port; a spring which yieldingly resists the movement of the piston in opposition to the suction and reacts from moving it in the opposite direction, the head of the cylinder having an annular recess to accommodate the spring, and a central outwardly-open chamber encompassed by said annular recess, the valve and operating connections therefor being located in said central outwardly-open chamber.
- 30 14. In combination, a large cylinder, and a small cylinder, a large piston and a small piston rigidly connected together and operating in said cylinders respectively; valve-controlled inlet and discharge passages for the small cylinder, the large cylinder having at the same side of the piston therein a suction port and an air inlet port which is larger than the suction port; a valve controlling said larger port; a lever operatively connected with the valve; a spring connected to one end of the lever and stressed past the lever fulcrum, whereby it tends to throw the valve to either limit upon being moved away from the opposite limit a certain distance, the piston being connected with the valve for initiating its movement with play at the connection for permitting the completion of the movement by the action of the spring.
- 35 15. In combination, a large cylinder, and a small cylinder, a large piston and a small piston rigidly connected together and operating in said cylinders respectively; valve-controlled inlet and discharge passages for the small cylinder, the large cylinder having at the same side of the piston therein a suction port and an air inlet port which is larger than the suction port; a valve controlling said larger port; a lever operatively connected with the valve; a spring connected to one end of the lever and stressed past the lever fulcrum, whereby it tends to throw the valve to either limit upon being moved away from the opposite limit a certain distance, the piston being connected with the valve for initiating its movement with play at the connection for permitting the completion of the movement by the action of the spring.

In testimony whereof I have hereunto set my hand at Chicago, Illinois, this 8th day of May, 1917.

WEBB JAY.
